(57) CLAIM

The ornamental design for a portable massager, as shown and described.

DESCRIPTION

FIG. 1 is a front elevation view of a portable massager, showing my new design in non-use condition;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof, in use condition;

FIG. 8 is a perspective view thereof, in non-use condition;

FIG. 9 is a front elevation view of a second embodiment of the portable massager, showing my new design in non-use condition; and,

FIG. 10 is a front elevation view thereof, opposite that shown in FIG. 9.

The only difference residing in FIGS. 9 and 10 is the shape of the end attachment with all other portions being identical to that shown in FIGS. 1-6.
